(57) **CLAIM**

The ornamental design for a seat, as shown and described.

DESCRIPTION

FIG. 1 is a rear top left perspective view of a seat showing my new design;

FIG. 2 is a rear top right perspective view of the design shown in FIG. 1;

FIG. 3 is a front top right perspective view of the design shown in FIG. 1;

FIG. 4 is a front top left perspective view of the design shown in FIG. 1;

FIG. 5 is a rear view of the design shown in FIG. 1;

FIG. 6 is a front view of the design shown in FIG. 1;

FIG. 7 is a right side view of the design shown in FIG. 1;

FIG. 8 is a left side view of the design shown in FIG. 1;

FIG. 9 is a top view of the design shown in FIG. 1; and,

FIG. 10 is a bottom view of the design shown in FIG. 1. The broken lines illustrate portions of the seat that form no part of the claimed design.
